US0D1072329S

(12) **United States Design Patent** (10) Patent No.: **US D1,072,329 S**
(45) Date of Patent: ** *Apr. 22, 2025

(54) **LIGHT FIXTURE**

(71) Applicant: **HLI SOLUTIONS, INC.**, Beachwood, OH (US)

(72) Inventors: **Qianshan Li**, Glendora, CA (US); **Michael Neuer**, Covina, CA (US); **Tomi Lin**, Irvine, CA (US); **Syed Raza**, Rancho Palos Verdes, CA (US); **Dean Dal Ponte**, Glendale, CA (US); **Prathika Appaiah**, Pasadena, CA (US); **Paul Lewis**, Greenville, SC (US); **Kevin Lu**, Fountain Valley, CA (US)

(73) Assignee: **HLI SOLUTIONS, INC.**, Beachwood, OH (US)

(*) Notice: This patent is subject to a terminal disclaimer.

(**) Term: **15 Years**

(21) Appl. No.: **29/784,902**

(22) Filed: **May 21, 2021**

(57) **CLAIM**

The ornamental design for a light fixture, as shown and described.

DESCRIPTION

FIG. 1 is a perspective view of a light fixture showing our new design.

FIG. 2 is another perspective view of the light fixture shown in FIG. 1.

FIG. 3 is a side view of the light fixture shown in FIG. 1.

FIG. 4 is a side view of the light fixture shown in FIG. 1, coupled to a support member; and,

FIG. 5 is a bottom plan view of the light fixture shown in FIG. 1.

The broken lines depict portions of the light fixture that form no part of the claimed design.

1 Claim, 5 Drawing Sheets
